CLAIM

The ornamental design for a display system with a virtual reality graphical user interface, as shown and described.

DESCRIPTION

This application is a continuation of and claims priority to U.S. application Ser. No. 29/619,026, filed Sep. 26, 2017, the contents of which are herein incorporated by reference in their entirety.

FIG. 1 shows a display system with a first embodiment of a virtual reality graphical user interface.

FIG. 2 shows a display system with a second embodiment of a virtual reality graphical user interface.

FIG. 3 shows a display system with a third embodiment of a virtual reality graphical user interface.

FIG. 4 shows a display system with a fourth embodiment of a virtual reality graphical user interface; and,

FIG. 5 shows a display system with a fifth embodiment of a virtual reality graphical user interface.

The outermost broken lines show the field of view for the display system and form no part of the claimed design. The broken lines showing portions of the graphical user interface form no part of the claimed design.

1 Claim, 5 Drawing Sheets
